W. T. LONG

PLIER WRENCH

Filed April 9, 1924

W.T. Long

Lacy Tracy, Attorneys

UNITED STATES PATENT OFFICE.

WILLIAM T. LONG, OF PUYALLUP, WASHINGTON, ASSIGNOR TO W. H. HURT, OF LONG BEACH, CALIFORNIA.

PLIER WRENCH.

Application filed April 9, 1924. Serial No. 705,308.

This invention relates to an improved plier wrench and seeks, among other objects, to provide a simple and convenient hand tool which may be used as a pair of pliers, as a wrench, and as a hand vise.

The invention seeks, as a further object, to provide a tool wherein a firm grip may be had upon the work and wherein the movable jaw of the device will partake of rectilinear movement with respect to the fixed jaw.

And the invention seeks, as a still further object to provide a device wherein by properly manipulating the hand levers of the tool, the movable jaw of the device will be automatically freed for unrestrained independent movement with respect to the fixed jaw so that the movable jaw may be manually adjusted or may be shifted by simply turning the device over when the movable jaw will shift by gravity.

Other and incidental objects will appear hereinafter.

In the drawings:

Figure 1 is a side elevation of my improved tool partly broken away and illustrated in section,

Figure 2 is a horizontal sectional view on the line 2—2 of Figure 1, looking in the direction of the arrows,

Figure 3 is a fragmentary vertical sectional view particularly showing the movable jaw of the device,

Figure 4 is a view similar to Figure 3, showing the feed dog of the movable jaw moved out of engagement therewith,

Figure 5 is a fragmentary side elevation showing a slight modification of the invention, and

Figure 6 is a fragmentary sectional view on the line 6—6 of Figure 5, looking in the direction of the arrows.

Referring now more particularly to the drawings, I employ a lever or stock 10 substantially V-shaped in cross section throughout the major portion of its length so that

the lever is thus provided with a reduced inner edge and pivoted upon said lever is a coacting channel-shaped lever 11. At its forward end, the lever 11 is provided with ears 12 straddling the lever 10 and extending through said ears and through the latter lever is a pin 13 pivotally mounting the lever 11. At its forward end, the lever 10 is formed with a head 14, at one end of which is provided a forwardly directed jaw 15.

As best brought out in Figures 2, 3 and 4 of the drawings, the head is channeled to define parallel side plates 16 and opening into the space between the plates is a recess 17 in the forward end of the lever 10. Opening into said recess is a cavity 18 above and forwardly of which is a shoulder 19, while at the bottom of the recess is provided a flat shoulder 20.

Mounted upon the head 14 to coact with the fixed jaw 15 is a movable jaw 21 on which is formed a shank plate 22. The shank plate is freely received between the side plates 16 of the head and is enlarged at opposite sides thereof to form a substantially cylindrical guide rib 23 snugly but slidably fitting in grooves 24 in the inner faces of the plates 16. Formed on the guide rib at its inner side, is a rack 25 extending from end to end of the rib and accommodated in the recess 17 to cooperate with said rack is a dog 26 which is provided with teeth to engage the teeth of the rack. Extending through the ears 12 of the lever 11 transversely through the recess is a pin 27 pivotally mounting the dog and formed on the dog at its lower end is a forwardly directed toe 28. Pressing the dog into engagement with said rack is a flat spring 29. At one end this spring is formed with a crook 30 which snugly fits within the cavity 18 of the lever 10 to expand thereagainst for removably supporting the spring to extend across the shoulder 19 and bear at its free end against the rear edge of the dog. It is observed that the channel, the recess and the cavity formed in the head 14 are in communication, that the shoulder 19 is disposed intermediate the recess 17 and the cavity 18 and that the depending toe 28 of the dog 26 coacts with the shoulder 20. Extending transversely between the side plates 16 of the head 14 at their lower forward corners is a removable pin 31 limiting the jaw 21 against displacement.

As best brought out in Figures 1, 3 and 4 of the drawings, the forward edges of the side plates 16 are formed to slope downwardly and rearwardly away from the adjacent face of the jaw 15 while the forward edge of the shank plate 22 of the jaw 21 is formed to slope upwardly and rearwardly in reverse direction so that the several edges will thus be disposed to fit adjacent flat faces of a nut or the like, and mounted upon the jaws 110

are coacting jaw members 32 and 33 respectively. These jaw members are formed with ears 34 to straddle the jaws and extending through said ears and through the jaws are 5 pins 35 detachably connecting said members with the jaws. At its inner end, the jaw member 32 is provided with an upturned lug 36 which is snugly received between the side plates 16 to rest flat against the rear edge 10 of the jaw 15, while the jaw member 33 is similarly provided at its inner edge with down turned lugs 37 to bear against the rear edge of the jaw 21 at opposite sides of the shank plate 22.

15 In the present instance, I have shown the jaw members as provided with teeth to engage the work but, of course, these jaws may be otherwise roughened or may be smooth, as may be desired. Secured at one 20 end within the lever 11 is a longitudinally bowed flat spring 38 which is arranged to extend forwardly and is notched at its free end to straddle the inner edge of the lever 10 so that the spring will thus coact between 25 the leaves for swinging the lever 11 away from the lever 10.

As will now be seen in view of the foregoing description, the dog 26 provides a connection between the lever 11 and the jaw 30 21 so that when the lever 11 is swung toward the lever 10, the dog will function to shift the movable jaw 21 toward the fixed jaw 15 for gripping the work. Upon the release of the lever 11, the spring 38 will immediately function to return the lever and since 35 the dog is tightly held against the rack 25 by the spring 29, the dog will serve to return the jaw 21 to its position away from the jaw 15. By pushing upon the jaw 21, this 40 jaw may be manually shifted toward the fixed jaw and thus initially adjusted with respect thereto, the rack 25 riding over the dog 26 as the movable jaw is shifted. However, the movable jaw cannot, as will be 45 seen, be adjusted away from the fixed jaw without the release of the dog. To accomplish this release of the dog, the lever 11 is, as shown in Figure 4, swung beyond its normal position away from the lever 10. 50 When in normal position the lever 11 is at the end of its throw by the spring 38. As will be seen, when the lever 11 is moved toward the lever 10, the pawl 26 is shifted upwardly away from the shoulder 20 while 55 when the lever 11 is released, the pawl is returned so that, as shown in Figure 3, the toe 28 of the dog abuts said shoulder for limiting the lever at the end of its throw by the spring 38. However, when the lever 11 is then further swung manually away from 60 the lever 10, the pivotal center of the pawl is swung further downward toward the shoulder 20 with the result that, as shown in Figure 4, the pawl is rocked, by reason

of the engagement of the toe 28 thereof with 65 the shoulder 20, away from the rack 25, flexing the spring 29. The movable jaw 21 is then, of course, freed for manual adjustment either toward or away from the fixed jaw 15 and, if desired, shifting of the jaw 70 may be accomplished simply by turning the tool over so that the movable jaw will gravitate either toward or away from the fixed jaw as desired. In operating the tool on a nut, for instance, the jaws may be released 75 by simply relieving the grip on the levers 10 and 11 when the jaws will spread sufficiently to permit the tool to be swung for a new hold. I accordingly provide a particularly effective structure for the purpose 80 set forth and a tool well adapted for a wide variety of uses.

In Figures 5 and 6 of the drawings, I have illustrated a slight modification of the invention wherein the jaws 39 and 40 of the 85 tool are provided at their outer ends with teeth 41 in the rear of which said jaws are formed with smooth faces adapted to grip a nut without mutilation thereof. Formed in adjacent side faces of the jaws are longitudinally tapered dove-tail slots 42 and removably wedged in said slots are coacting cutters 43, the confronting faces of the jaws, at said slots, being provided with mating 90 channels 44 to accomodate the object to be severed by the cutters. Otherwise, the modified structure is identical with the preferred embodiment of the invention and further description is accordingly believed 95 unnecessary.

Having thus described the invention, what I claim is:

A tool of the character specified comprising a fixed handle member having a head at one end terminating in a jaw and formed with a communicating channel, recess and cavity, the recess having a shoulder upon the forward portion of its bottom and there being another shoulder intermediate the recess and cavity, a movable jaw mounted in the channeled head and having its rear portion toothed to provide a rack, a pin supported in the head upon opposite sides of the channel to prevent displacement of the movable jaw and limit its outward movement, an operating member pivoted to the head, a dog pivoted to the operating member and having a depending toe to coact with the said first mentioned shoulder to disengage the dog from the movable jaw whereby the latter may be freely adjusted, and a flat spring crooked at one end and fitted into the said cavity and having its opposite end engaging the dog and retained in place by the said second mentioned shoulder.

In testimony whereof I affix my signature.
WILLIAM T. LONG. [L.S.]
